UNITED STATES PATENT OFFICE.

CHARLES F. NEHRKE, OF NEW YORK, N. Y.

RADIOINDICATOR.

Application filed June 15, 1927, Serial No. 188,923, and in Germany June 28, 1926.

This invention relates to radio indicators or tuning devices and has particular reference to dials or indicators which are preferably though not exclusively employed in connection with vernier or slow adjustment means for delicacy of operation.

Among the objects of the invention is to provide means for facilitating the adjustment of the dial mechanism or condenser in such a manner that the readjustment for the same station may be easily effected thereafter.

More specifically, an object of the invention is to provide peculiarly arranged lighting means whereby the indication of individual stations or the like is materially facilitated.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a vertical sectional view of one form of the invention.

Fig. 2 is a front elevation of the same structure.

Fig. 3 is an enlarged detail view of the lighting features shown in Fig. 1.

Fig. 4 is a front elevation of a fragment of a different type of indicator member.

Fig. 5 is a vertical transverse section on the line 5—5 of Fig. 4.

Fig. 6 is a fragmentary front elevation of a further modification.

Fig. 7 is a vertical section on the line 7—7 of Fig. 6.

Fig. 8 is a detail view of a feature shown in Fig. 7.

Referring now more specifically to the drawings, I show at 10 a section of the cabinet or tuning panel through which projects as usual a shaft 11 of the condenser or any other instrument that should be adjusted. 12 indicates a shell or casing adapted to be secured to the panel 10 by any suitable means such as screws or bolts passing through holes 13, the rim or flange 14 of the casing bearing against the surface of the panel. Journaled in a central bearing 15 of the casing is a knob 16 which by means of a set screw 17 or its

equivalent is secured firmly to the outer end 55 of the condenser shaft 11. In the upper portion of the casing is formed a wide arc-shaped slot or opening 18 adjacent to the ends of which are a pair of clamping nuts 19, said opening being normally closed except for a smaller window 20 by means of a cover plate 21 which is substantially co-extensive with the main opening or window 18. The small window 20 is formed in the cover plate 21.

Within the casing 12 and between the face 65 thereof and the panel 10 is located an indicator dial or disk 22 fixed firmly to the inner end of the knob 16 as by upsetting the end of the knob at 23. One portion, for example the lower edge portion, of the dial 22, is 70 driven by some manual means including a knob 24 for relatively slow rotation which is communicated to the shaft 11. This means for communicating such rotational movement is shown as effected by means of a friction driving gear 25 journaled in the lower portion of the casing with the knob 24. Any other suitable means, however, for adjusting the dial may be employed. An arc-shaped slot 26 is formed in the dial concentric with 75 the axis thereof and extends approximately one-half the circumference thereof. This slot is adapted to register approximately with the large window 18. Fixed over the front of the disk or dial 22 adjacent to the slot 26 is a keeper 27 of preferably spring material such as spring metal, forming a shallow pocket 80 for the reception of an arc-shaped strip of film 28 of black celluloid or any other equivalent material which covers and closes the slot 26. The film 28 being held in the keeper or pocket 27 and thereby carried with the dial 22, these parts all rotate together according to the adjustment or manipulation of the knob 24.

The face plate or shutter closely within or below the small window 20 is provided with a depression 29 having a small hole 30 brought thereby into close proximity with the film 28 which spans the slot 26. One purpose of the large window 18 is to provide substantially free access to the slotted portion of the dial or disk 22 when the shutter 21 is removed by the loosening of the thumb nuts 19, thereby giving access directly to the keeper or pocket 27 for the inspection or replacement of the film 28 and other purposes. The face of the dial 22 is provided with any

suitable graduation or identification marks such as are indicated in Fig. 2 through the small window 20 as is customary in connection with tuning dials. Co-operating with this graduated portion of the dial is a pointer 31 extending upward or outward radially from the region of the socket 29 and perforation 30.

Located in any convenient manner in or adjacent to the panel 10 and back of the graduated portion of the dial is a source of light 32 which preferably may be any suitable type of electric lamp in circuit with the A battery of the machine or otherwise. 33 15 indicates the lever of a switch for closing or opening the circuit through the lamp. The lamp is located so as to have its axis projecting forward through the slot 26 and hole 30.

As thus far described the invention as to its mode of operation may be briefly summarized as follows: With the parts constructed as described and with a film 28 located in the pocket or keeper 27 between the hole 30 and the slot 26, the tuning or adjustment of the instrument will be performed in accordance with the usual practice by the turning of the knob 24 one way or the other until the desired station is determined. When so properly adjusted, the operator by the means of a pin 30 or equivalent sharp pointed instrument will prick through the hole 30 and make a small perforation 28^a in the film 28. At any subsequent adjustment or tuning for the same station therefore, the operator may turn the dial until he observes a ray or gleam of light from the lamp 32 through the registering holes 28^a and 30. And this either with or without observing the reading of the scale.

Another reason for making the dial and film mechanism easily accessible, as by removing the shutter 21, is to enable the operator to slip between the film and the main portion of the disk or dial 22, bits of colored materials such as thin celluloid. With a sufficient number of these bits of celluloid or pieces of colored material, a number equivalent perhaps to the total number of stations that may be patronized, a distinctly different color for each station, the adjustment of the dial after the colored bits have been inserted will cause the distinctive color of light to be emitted through the peep hole 30. Hence the operator will be able to tune for any familiar station even in the dark when he may be unable to read the marks on the scale, simply by observing the different colors of light. It will of course be understood that the colored bit will be inserted into its place after the hole 28^a is formed so that the colored bit will not be perforated or punctured.

In the modification of Figs. 4 and 5, the same inventive idea is disclosed, but with a changed form of movable indicator or carrier. In the modified form a drum shaped carrier 22^a is provided, the same having a

flange 22^b projecting forward through a slot 35 formed in a face plate 36 mounted on the front of the cabinet. This face plate corresponds broadly to the shutter 21 above described, it being provided with a depression 70 or socket 29 and a hole 30 adjacent to which is the pointer 31 registering with a series or succession of spaces for station indicia indicated at 37 on the cylindrical face of the member 22^a, the main portion of which is preferably 75 of white or opal colored celluloid 38 through which light from the lamp 32 within the carrier is made visible through the translucency or partial transparency of the strip of material 38. Along one edge of this strip 80 or constituting in effect a lateral extension thereof is a narrow strip of opaque material 28^b which when the carrier is turned around its axis is caused to move along just back of the perforation 30 and through which the 85 sharp pointed instrument may cause to be made a series of prick marks or holes 28^a through which the light will shine as above described from the lamp 32. These holes 28^a correspond as already described to the names 90 or initials of the several stations which are indicated in succession by the pointer 31.

In Figs. 6 and 7 I show a variation of indicator means including a graduated disk 22^c mounted back of or within the casing panel 10^c, the same being fitted with a window plate 39 having a series of radial holes 40 and a window 41. The window registers with an arc-shaped scale 42 carried by the dial or disk, and 43 indicates an arc-shaped strip of opaque material or film just back of the series of holes 40. 44 indicates a plate carried by the fixed structure and having a slot 44^a registering with the holes 40 and lying back thereof. This plate and slot provides a backing so that the strip 43 may be punctured with a sharp pointed instrument through any one of the radial holes 40 or combination of such holes as indicated at the right side portion of Fig. 6. Back of the plate 44 is a rim 45 composed of a succession 100 of various colors of translucent material somewhat as described above, but of larger scope so that they may be thought of as being fields for the indication of groups of stations. By means of the plate 44 a sharp instrument of 105 limited length in one or more of the holes in each series of holes 40 may be employed without danger of puncturing the colored plate. More definitely, considering one of the bits of color as the basis for a group of 110 stations, the several stations in the group will be identified or distinguished from one another by the number and location of the perforations made at 43^a. It is therefore readily possible and expedient for any reasonable 115 number of independent stations to be distinguished by the light indications alone after the proper markings are made by the puncturing instrument. This form also includes a lamp 32 with a suitable switch in the form 120 125 130

of a screw 33^a. The switch mechanism in all forms of the invention being conventional, is not shown in detail.

I claim:

- 5 1. In an instrument indicator of the character set forth, a casing having a pin hole and a window in proximity thereto, control means adapted to operate a tuning device mounted on the rear side of the casing, a dial mounted 10 at the rear of the casing and coacting with the control means to move with said device, said dial having markings adapted to be seen through said window, said dial being adapted to be easily punctured in the aforesaid position 15 by a tool inserted through the panel pin hole, said dial having a series of pin holes punctured therein and registering successively with the casing pin hole, the dial pin holes being correlated with the said markings for 20 indicating the setting of the device, and a source of light to the rear of the dial, the light

whereof is visible through the casing pin hole when a pair of pin holes are in registry.

2. In an instrument indicator of the character set forth, a casing having a pin hole, 25 control means adapted to operate a tuning device mounted on the rear side of the casing, an opaque dial mounted at the rear of the casing and adapted to move with said device, said dial being adapted to be easily punctured in the aforesaid position by a tool inserted through the casing pin hole, said dial having a series of pin holes therein adapted to successively register with the casing pin hole on movement of the control means, materials of different colors associated with the dial pin holes, and a source of light to the rear of the dial, the light from which can be seen in various colors through the casing pin hole to indicate the setting of the device. 40

In testimony whereof I affix my signature,
CHARLES F. NEHRKE.
